J. J. SHEA.
SEPARATING DEVICE FOR RUBBER MILLS.
APPLICATION FILED AUG. 10, 1916.

1,249,216.

Patented Dec. 4, 1917.

WITNESS:

Scottay, Ltd.

INVENTOR

John J. Shea,

BY
Ernest Hopkinson
HIS ATTORNEY

UNITED STATES PATENT OFFICE.

JOHN J. SHEA, OF HARTFORD, CONNECTICUT, ASSIGNOR TO THE HARTFORD RUBBER WORKS COMPANY, A CORPORATION OF CONNECTICUT.

SEPARATING DEVICE FOR RUBBER-MILLS.

1,249,216.

Specification of Letters Patent. Patented Dec. 4, 1917.

Application filed August 10, 1916. Serial No. 114,123.

To all whom it may concern:

Be it known that I, JOHN J. SHEA, a citizen of the United States, residing at Hartford, county of Hartford, and State of Connecticut, have invented certain new and useful Improvements in Separating Devices for Rubber-Mills, of which the following is a full, clear, and exact description.

This invention relates to devices used to 10 separate a batch of rubber on the upper sides of the rolls of a mill so that a more thorough mixing of the batch will be produced. An object of the invention is to provide a device of this character which may 15 be maintained in operative position adjacent to the rolls, and may be held in inoperative position removed from the rolls, when desired.

The invention can be readily understood 20 from the following description taken in connection with the accompanying drawing, in which—

Figure 1 is a side elevation of the device. Fig. 2 is a front elevation of the device.

25 Referring now to the drawing, in which like characters of reference designate similar parts, 10 and 11 designate a pair of rolls of a rubber mill, illustration of the mill itself being omitted for the sake of brevity. 30 and clearness. The separating device comprising the subject matter of this invention, embodies a support 12 which may be bolted or otherwise secured to parts 13 of the mill frame above the rolls. The support is provided with bearings 14 which receive a hinge pintle 15 that is fixed in the bearings by a set screw 16. Above the pintle the bearings are provided with registering openings 17 for a purpose which will presently appear.

40 A plow 18 of the general outline shown in Fig. 1 is provided with hinge eyes 19 which register with the bearings 14 and receive the above mentioned pintle 15. The plow is thus hinged to the support and may be 45 swung downward to operative position between the upper sides of the rolls midway between the ends of the rolls, or may be swung upward in inoperative position horizontally above the rolls, as indicated in 50 dotted lines in Fig. 2.

Projecting obliquely upwardly from the hinge eyes of the plow are ears 20 which are provided with openings 21 that are adapted to register with the openings 17 in the bear-

ings and receive a pin 22 which locks the 55 plow stationary in operative position. A spring pressed pin 23 is mounted in one of the ears 20 and seats terminally in a circumferential groove 24 formed in the pin 22, and holds the latter against accidental 60 escape.

When it is desired to remove the plow from operative position, the pin 22 is withdrawn and the plow is rocked upward to extend laterally over the rolls, in which position the openings 21 in the ears 20 will be disposed below the bottom edges of the bearings 14. The pin 22 is now inserted in said openings and lodges underneath said bottom edges so that the plow is held up in 70 inoperative position removed from the rolls.

In operation, when the plow is locked in operative position to extend downward between the rolls, the rubber stock which accumulates on the front roll of the mill in 75 a thick layer, will be severed progressively by the plow and deflected from the sides of the plow into the batch in the usual and well known manner. When it is desired to put a new batch of rubber stock in the mill, the 80 plow may be rocked up out of the way and locked in inoperative position as above described.

Having thus described my invention, what I claim as new and desire to protect 85 by Letters Patent is:

1. A separating device for mills comprising a support, a plow, and means for pivotally connecting the plow to the support 90 adapting the plow to be swung in the direction of the axis of the mill rolls into and out of operative position.

2. A separating device for mills comprising a support, a plow hinged on the support and adapted to swing downward to 95 operative position adjacent the upper sides of the rolls of the mill, and adapted to be swung upward to inoperative position laterally above said rolls, and means for locking the plow stationary on said support in operative or inoperative positions.

3. A separating device for mills comprising a support having bearings thereon, a plow hinged on said bearings and adapted 100 to be swung to operative position adjacent the upper sides of the rolls of the mill, and adapted to be swung to inoperative position laterally above said rolls, and means engag-

ing said bearings and an integral portion of the plow and holding said plow stationary in operative or inoperative positions.

4. A separating device for mills comprising a support having bearings thereon, a plow hinged on said bearings and adapted to be swung to operative position adjacent the rolls of the mill, and adapted to be swung into inoperative position laterally above said rolls, a pin adapted to engage a projecting portion of the plow and said bearings to lock the plow stationary in operative or inoperative positions, and

means on the plow engaging and holding said pin against accidental escape from 15 place.

5. A separating device for mills comprising a support, a plow, means for pivotally connecting the plow to the support adapting the plow to be swung in the direction 20 of the axis of the mill rolls, and means for securing the plow in operative position.

Signed at Hartford, Conn., this 22 day of July, 1916.

JOHN J. SHEA.
